GEORGE HENRY GILMAN AND HENRY MILLS ROBERTSON, OF ST. PAUL, MINNESOTA.

UNCOUPLING MECHANISM.

1,113,983.

Specification of Letters Patent.

Patented Oct. 20, 1914.

Application filed January 12, 1914. Serial No. 811,615.

To all whom it may concern:

Be it known that we, GEORGE H. GILMAN and HENRY M. ROBERTSON, citizens of the United States, residing at St. Paul, in the 5 county of Ramsey and State of Minnesota, have invented certain new and useful Improvements in Uncoupling Mechanism, of which the following is a specification.

Our invention relates to uncoupling devices, that is to say, to devices for drawing the locking pins of car couplers so as to release the knuckles.

One of the principal objects of the invention is to provide an uncoupling device 10 adapted to be connected directly to the locking pin of the coupler with an engagement which, while it permits the normal movements of the coupler sidewise and inwardly and outwardly, operates automatically and 15 with positiveness and certainty to draw the pin when the outward movement of the coupler exceeds the normal, for example, through a failure of some part of the draft rigging; so as to thereby release the coupling 20 between the cars and obviate the danger of the coupler or some portion of the draft rigging falling down upon the track and derailing the rear section of the train. In certain types of couplers the locking pin, 25 cause of its contour and relation with the coupler head, in order to be drawn from the locking to the lock set position has to be given, at least initially, a free, accurately vertical movement. Our uncoupling mechanism takes this circumstance into account 30 by a construction which, in the automatic uncoupling operation, assures to the pin this initial free vertical movement, thereby obviating the danger of having the pin bind 35 in the coupler and defeat the intended automatic uncoupling with consequent possible injury to or destruction of the mechanism.

A further object of the invention is to provide an uncoupling apparatus, the parts 40 of which are so constructed and arranged that when the locking pin is in the lock set position the apparatus supports itself in its corresponding position and thereby assists in keeping the pin lock set instead of making 45 the lock set position of the pin unstable, as is the case with many forms of uncoupling apparatus. Because of this feature of the invention the switchman after drawing the pin, in cutting a car for example, can let 50 go of the apparatus without fear of having 55

the pin accidentally dislodged and returned to the locking position.

A further object of the invention is to provide an uncoupling device having a direct connection with the coupler pin, instead of the chain connection formerly used, and having the automatic uncoupling function above noted, which will be extremely simple in its construction, economical to manufacture and very strong and durable. 60

In the preferred embodiment of our invention shown the device consists of a single rod or lever mounted in a pair of bearing members which can be cheaply manufactured and readily attached to car sills of various 65 types.

The invention has for further objects such other new and improved constructions, arrangements and devices relating to uncoupling mechanism as will be hereinafter 70 described and claimed.

The invention is shown, in certain preferred embodiments, in the accompanying drawings wherein—

Figure 1 is a plan view of one form of the 75 invention shown as applied to a box car; Fig. 2, an elevation of the device; Figs. 3, 4 and 5, detail side views showing the coupling lever and pin upon which it operates in different positions; Fig. 3 showing the relative position of the parts when the pin is in its locking position, Fig. 4 the position assumed by the same parts during the automatic uncoupling operation, and Fig. 80 85 90 95 100 105 110

5 the relation of the parts when the pin is in lock set position; Fig. 6, a plan view illustrating a modification, and Figs. 7 and 8, side views of the same, showing portions of the car in longitudinal section, Fig. 7 showing the pin in locking position and Fig. 6 showing it being automatically drawn.

Like characters of reference designate like parts in the several figures of the drawings.

Referring first to Figs. 1 to 5 inclusive, 10 designates a coupler which will be recognized as a familiar construction, and 11 the locking pin thereof which is shown as formed with an eye 12. The uncoupling element or lever consists of a rod 13 bent at one end so as to form a handle 14 and at the other end so as to provide a crank 15 formed with a member 16, substantially parallel with the end of the car, which extends through the eye 12 of the locking pin. The outer end of the uncoupling element 13 is 110

supported revolvably in a bearing member 17 and the inner end, that is the cranked end, in a bearing member 18. The latter is formed with an elongated bearing slot 19 which has an upward inclination in the direction away from the car. The purpose of giving the bearing slot this upward inclination is two-fold: first, to impart in the automatic uncoupling operation of the mechanism an initial free vertical movement of the locking pin, and second, to give the lever stability when the pin is in the lock set position so that it will aid in keeping the pin in this position instead of having a tendency to dislodge it therefrom. In Fig. 3 the pin 11 is shown in its normal locking position. There is some looseness in the engagement between the lever and the eye 12 of the pin. This permits the normal movements of the coupler from side to side and also the normal movements inwardly and outwardly. In respect to the latter movements the cam action upon the lever resulting from the upward inclination of the bearing slot is compensated by the lost motion of the connection between the lever and the pin for any normal outward movement of the coupler. If the draft gear fails for any reason so that the coupler is drawn outwardly beyond the point contemplated by the intended compression or tension of the draft springs, the lever will be moved to the outer end of the slot 19 and at the same time will be raised due to the upward inclination of the slot. As the handle 14 bears against the sill of the car, designated 20, the locking pin will be correspondingly raised. This movement of the pin will be a free vertical movement. The position of the parts at the end of this initial free vertical movement of the pin is shown in Fig. 4. A further outward movement of the coupler will cause the pin to rise (assuming that the construction of the coupler requires a further vertical movement of the pin in drawing), the uncoupling lever rotating axially to permit this. The movement of rotation results from the preferred arrangement of the bearing slot 19 above the eye 12 of the pin when the latter is in the position shown in Fig. 4. If, on the other hand, the coupler is so constructed that the pin may be drawn by simply pulling it backwardly, the lever does not need to rotate. In certain types of coupler such, for example as the coupler known as the "Simplex" coupler shown in the drawings, it is necessary to give the pin an initial free vertical movement before it can be drawn. With such a coupler, if the uncoupling force is initially applied so as to pull the pin backwardly as well as upwardly, the pin will cramp and the desired automatic uncoupling will be defeated, with the possible consequence of pulling the uncoupling device away from the car. The initial cam actuated movement which our apparatus is capable of accomplishing and which is essential to accomplish the automatic uncoupling of couplers of the Simplex type, is of advantage if not an essential 70 in the case of other couplers since it obviates the possibility of the pin binding. Fig. 5 illustrates the second mentioned function resulting from the inclination of bearing slot 19. This figure shows the locking pin in its lock set position. When the locking pin of the coupler is in this position and the uncoupling mechanism has a direct connection with the pin, instead of the chain connection which was formerly used but is now condemned by the authorities, the connection of the uncoupling mechanism to the pin is, in many cases, the cause of instability since the weight of the uncoupling 75 mechanism and its vibration when the train is in motion may easily dislodge the pin from such lock set position. In cutting cars, therefore, the switchman frequently has to run along the side of the train and hold up the uncoupling lever. This is difficult work and often dangerous, particularly if from the position of the train the switchman is out of sight of the engineer. By giving the elongated bearing slot in the inner bearing member the inclination 80 shown, the lever, when in a position corresponding to the raised position of the pin, will set back in the slot due to the fact that the portion of the lever inside of bearing 85 17 is much heavier than and hence overbalances the portion beyond the bearing, that is, the handle 14. As a result the lever tends to hold the pin in its lock set position, as clearly shown in this figure, instead of 90 being an element of instability. The switchman therefore, in cutting cars for example, may withdraw the pin and then let go of the lever without fear that the pin will be dislodged and returned to its locking position. 95 The advantage of doing this is particularly apparent in case, as sometimes happens, the train stands on a curve at the time the car is uncoupled so that the switchman when he has hold of the uncoupler element cannot be seen by the engineer. With the stability of the lock set position of the pin assured the switchman after drawing the pin can leave the train and go to such point to 100 one side thereof as may be necessary in order to give the engineer the starting signal. This obviates one serious cause of danger to 105 life and limb in the switching of cars. 110 In Figs. 6 to 8 inclusive, the extremity of the coupler lever on the other side of the locking pin from the bearing member is connected to the sill of the car by means of a short chain 21. This chain, as shown particularly in Fig. 8, is intended to tauten at 115 the moment in the automatic uncoupling op- 120 125 130 135

eration at which the lever reaches the end of slot 19 so as to take up some of the pull on the lever and thereby strengthen the mechanism against the very severe shock which it receives when the coupling parts. In these figures the uncoupling device is fitted to a caboose car, the platform of which is indicated at 22, and a slack chain 23 is provided extending from the extremity of the uncoupling lever to the upper part of the platform rail 24 of the car for convenience in pulling the pin when the switchman is on the car platform.

While we have shown and described our invention in certain preferred embodiments we do not wish to be understood as limiting the invention to the precise constructions, arrangements and devices shown except so far as such constructions, arrangements and devices are specifically made limitations in certain of the claims herein.

We claim:

1. Uncoupling mechanism comprising a revoluble uncoupling element adapted to be engaged directly with the locking pin of a coupler, a bearing member for the end of said element remote from the coupler and a bearing member for the other end of said element provided with an elongated bearing slot in which said element is slidably as well as revolubly mounted which slot is inclined from the horizontal at an angle which causes the rod to positively move the pin vertically from its locking position when the coupler moves outwardly beyond its normal outer limit.
2. Uncoupling mechanism comprising a revoluble uncoupling rod formed at the outer

end with an angularly disposed handle and at the other end with a cranked portion adapted to extend through the eye of the locking pin of a coupler, a bearing member for the outer end of said rod, and a bearing member for the inner end thereof provided with an elongated bearing slot in which said rod is slidably as well as revolubly mounted, which slot is inclined from the horizontal at an angle which causes the rod to positively move the pin vertically from its locking position when the coupler moves outwardly beyond its normal outer limit.

3. Uncoupling mechanism comprising a revoluble uncoupling rod formed at the outer end with an angularly disposed handle and at the inner end with a cranked portion adapted to extend through the eye of the locking pin of a coupler, a bearing member for the outer end of said rod, a bearing member supporting the rods between the handle and the cranked portion thereof provided with an elongated bearing slot above the eye of the pin in the locking position of the latter in which said element is slidably as well as revolubly mounted, and means providing a loose connection between the inner extremities of the rod and the end of the car which allows the rod to move in and out to the extent of the normal movement of the coupler which transmits the stress on the rod to the end of the car if the coupler moves outwardly beyond its normal limit.
